UNITED STATES PATENT OFFICE.

WILLIAM KOLLER, OF POMEROY, WASHINGTON.

WEEDING MACHINE.

Application filed July 14, 1923. Serial No. 651,581.

To all whom it may concern:

Be it known that I, WILLIAM KOLLER, a citizen of the United States, residing at Pomeroy, in the county of Garfield and State of Washington, have invented certain new and useful Improvements in a Weeding Machine; and I do hereby declare the following to be a full, clear, and exact description of the invention, such as will enable others skilled in the art to which it appertains to make and use the same.

This invention relates to a weeding machine.

It is aimed to provide a novel construction of machine adapted to more expeditiously and efficiently cut the weeds and particularly one having a rotatable cutter provided with one or more helical cutting edges.

Another object is to provide a construction in which the said cutter may be formed by the twisting of a rod or bar.

It is further aimed to provide a novel construction of machine adapted to carry the cutter, to permit efficient adjustment and variation in the position thereof and with a view to driving the cutter through the movement of the ground wheels of the machine or implement.

Additional objects and advantages will become apparent from a consideration of the description following taken in connection with accompanying drawings illustrating an operative embodiment.

In said drawings:

Figure 1 is a plan view of the machine;

Figure 2 is a front elevation thereof;

Figure 3 is an end elevation of the machine with one of the wheels removed,

Figure 4 is a cross sectional view of the line 4—4 of Figure 1, and

Figure 5 is a detail sectional view illustrating the pawl and ratchet connection between the wheels and axle of the machine.

Like reference characters designate like or similar parts in the different views.

In reducing the invention to practice, a substantially rectangular frame is provided as at A having end beams at 10 and horizontal beams 11. Depending from the end beams 10 are bearings or hangers 12 in which a shaft or axle 13 is journaled. Ground wheels 14 are fastened to the axle 13 in such a manner that when the machine moves forward the axle will turn with such wheels but should the machine be backed, the wheels

will rotate independently of the axle, such result being brought about by a pawl and ratchet and hub and shaft connection of usual or approved form.

Frame A is provided with an intermediate horizontal beam at 15 and, at suitable spaced intervals along the same, risers or blocks 16 are secured.

A supporting beam 17 for the cutter to be later described extends substantially parallel with the beams 11 and 15 and is hinged on horizontal axes as at 18 to the risers or blocks 16. The position of beam 17 may be varied through the manipulation of an arm or lever 19 having divergent straps 20 secured to the upper and lower surfaces of beam 17 and movable relatively to and adapted to be locked to a plate or segment 21. This plate or segment 21 is fastened at one end to one beam 11 and at its other or upper end to a post 22 which rises from the frame A and is braced by means of a diagonal rod as at 23. Plate 21 is notched as at 24 in order to receive a locking plunger or the like 25 carried by lever 19, selectively, in order to fasten such lever in different positions and accordingly the bar 17 in different positions.

Substantially U-shaped hangers 26 are connected by horizontal pivots 27 to the beam 17 on substantially horizontal axes, and to eye bolts 28 of one of the beams 11. At the lowermost portion of the hangers 26 are carried suitable blocks or bearings 29 in which an elongated cutter 30 is journaled by means of round portions 31.

Said cutter 30 consists of a metallic rod or bar which is twisted so that it will have the portions 31, and helical ridges or cutting edges 32.

Rotary motion is imparted to the cutter 30 in any suitable manner. For instance, a gear wheel 33 may be keyed to the shaft or axle 13 and disposed in mesh with a smaller gear wheel or pinion 34 keyed to a shaft 35 which is journaled in hangers or brackets 36 suitably fastened to and depending from the frame A. The shaft 35 has a ball and socket connection at 36 with a link 37 having a link 38 extensibly connected therewith for unitary turning with the same and which link 38 is universally connected as at 39 to one end of the cutter 30.

A seat 40 may be provided for the driver on the frame A and a draft tongue 41 may extend from such frame.

Hangers or brackets 26 may be reinforced

by braces 40 and 41 which are pivoted to beam 17 at 42 in line with pivots 27 and to brackets 26 by studs 43 passing pivotally through brackets 26 and braces 40 and secured in place by nuts 44 threaded on said studs 43.

In use, the handle or lever 19, with the lock 25 retracted, is adjusted vertically so as to place the cutter 30 relatively close to 10 and in proper position with respect to the ground or weeds to be cut. The parts are locked in adjusted position through the release of the lock 25 and its engagement with the appropriate notch 24. The movement of the bar 17 controlling the position of cutter 30 is permitted by the hinge or pivotal connections at 18, 27 and 28. The adjustment of the cutter does not affect the driving connection thereof with the gear 20 wheels 33 and 34 in view of the extensible or slip connection of the links 37 and 38. As the machine is drawn over the weeds, the rotation of ground wheels 14 forwardly will correspondingly rotate the axle 13 so that through the medium of the gear 25 wheels 33 and 34, shaft 35 is driven. The cutter is driven from shaft 35 in view of the connection of the links 37 and 38 therewith at 36 and 39, respectively. As the cutter 30 rotates, the cutting edges 32 are brought into 30 engagement with the weeds in advance of the cutter so that the latter will be hewn or cut from their roots relatively close to the ground.

Changes in the details may be resorted to 35 provided they fall within the spirit and scope of the invention.

Having thus described the invention, what I claim is:

40 1. A weeder having a frame, axle carried by said frame, ground wheels to drive said axle, a beam extending longitudinally of

the frame, risers on said beam, a second beam, said second beam being hinged to said risers, a post rising from the frame, a 45 lock member secured to said post and frame, an adjusting lever leading rigidly from said second beam and having means for locking engagement with said lock member, substantially U-shaped hangers pivoted to the second beam and to the frame, bearings carried by said hangers adjacent their lower ends, a cutter journaled in said bearings, a gear wheel on said shaft, a gear wheel driven by said gear wheel, and a link connection between the second gear wheel and said cutter.

2. A weeder having a wheeled frame, said frame having a longitudinal beam, a second longitudinal beam on said frame, a beam 60 pivoted to the second longitudinal beam and disposed on the side thereof opposite to the first mentioned beam, articulate hangers connected to the first mentioned beam and to the third mentioned beam, a 65 cutter mounted by said hangers, means on the frame to adjust the third mentioned beam to vary the position of the cutter consisting of a post rising from the frame, a locking plate connected to the post and to 70 the frame, an adjusting lever rigidly connected to the third mentioned beam and having latch means associated with said locking plate, and a brace extending from the post on the opposite side thereof to the 75 locking plate and across the second and third mentioned beams and fastened to the first mentioned beam.

In testimony whereof I affix my signature in presence of two witnesses.

WILLIAM KOLLER.
